UNITED STATES PATENT OFFICE.

ARTHUR S. PIERSON, OF MORRISTOWN, NEW JERSEY.

MAILING-PACKAGE.

No. 909,330.

Specification of Letters Patent.

Patented Jan. 12, 1909.

Application filed March 11, 1908. Serial No. 420,335.

To all whom it may concern:

Be it known that I, ARTHUR S. PIERSON, a citizen of the United States, and residing at Morristown, in the county of Morris and 5 State of New Jersey, have invented certain new and useful Improvements in Mailing-Packages, of which the following is a specification, such as will enable those skilled in the art to which it appertains to make and use 10 the same.

This invention relates to packages for use in mailing papers, drawings, lithographs and various other kinds and classes of articles, and the object thereof is to provide an improved package of this class which is simple in construction and comparatively inexpensive, and which may be easily closed or sealed whenever desired and also as easily opened; a further object being to provide a 20 mailing package in the form of a tube having improved end closing devices.

The invention is fully disclosed in the following specification, of which the accompanying drawings form a part, in which the separate parts of my improvement are designated 25 by suitable reference characters in each of the views, and in which;—

Figure 1 is a side view of a tubular package provided with my improved closing devices, 30 the end portions being in section, Fig. 2 an inside view of one of the closing devices detached, Fig. 3 a view similar to Fig. 2, but showing a modification.

In the drawings forming a part of this specification, reference being made to Figs. 1 to 3 inclusive, I have shown at *a* an ordinary mailing package the body portion of which is tubular in form and composed of card-board, paste-board or other fibrous material, and the ends 40 of which are closed by caps *b* composed of similar material. The caps *b* are provided with flanges or rims *b*² adapted to inclose the ends of the body portion of the package and to closely fit the same, and in the practice of 45 my invention I provide, in the form of construction shown in Figs. 1 and 2, metal strips *c* which are passed through the flanges or rims *b*² closely adjacent to the body portion of the caps *b*, and the length of which is 50 greater than the diameter of said caps. The metal strips *c*, at their ends, are bent to form parts *c*² the length of which is equal to the width of the flanges or rims *b*² of the caps *b*, and the end portions of the parts *c*² are bent

to form inwardly directed barbs or prongs *c*³ adapted to be passed inwardly through the walls of the body of the package *a*.

Inclosing the ends of the body of the package, the caps *b* are placed on said ends and the parts *c*³ are forced through the walls thereof as clearly shown at the left hand end of Fig. 1, and in this way the ends of said package are securely closed, and in order to open the same the barbs or prongs *c*³ must be drawn out or the caps destroyed. The closure device shown in Fig. 3, is the same as that shown in Fig. 2, except that only one of strips *c* is employed.

My improved end closure device or devices for packages of the class herein shown and described, as will be understood, may be used over and over again, as the locking devices or parts *c*² and *c*³, are flexible and the removal or detaching of the closure devices in order to open the package does not necessarily destroy said parts, and while I have described the body portions of the closure device as composed of fibrous material, it will be apparent that other material may be employed.

Having fully described my invention, what I claim as new and desire to secure by Letters Patent, is;—

1. A package device composed of a hollow body portion and provided with an end closure device comprising a cap having a rim adapted to inclose and closely fit the end of the body portion, and the inner side of which is provided with a transverse flexible strip the ends of which pass through said rim and project beyond the side of the cap and are adapted to be folded transversely of the rim and passed inwardly through the body portion.

2. A package device, comprising a tubular body portion and provided with an end closure device comprising a cap having a rim adapted to inclose and closely fit the body portion, said cap being provided on its inner side with a transverse flexible strip, the ends of which pass through said rim and project beyond the side walls of the cap a distance greater than the transverse width of said rim, said ends of said strip being adapted to be folded transversely of said rim and the ends thereof to be passed through the body portion adjacent to said rim.

3. A package device composed of a hollow

tubular body portion provided with end closure devices comprising caps having a rim adapted to inclose and closely fit the end of the body portion, said caps being provided with transverse flexible strips which are passed through the rims thereof closely adjacent to the inner side of the caps, and the ends of which project a distance greater than the transverse width of the rims, said ends of said strips being adapted to be folded transversely of the rims and passed inwardly

through the body portion of the package device.

In testimony that I claim the foregoing as my invention I have signed my name in presence of the subscribing witnesses this 7th day of March, 1908.

ARTHUR S. PIERSON.
